UNITED STATES PATENT OFFICE.

WALTER M. UPCHURCH, OF MOGOLLON, NEW MEXICO.

DESIGN FOR A POISON BOTTLE OR RECEPTACLE.

49,785.

Specification for Design.

Patented Oct. 17, 1916.

Application filed March 3, 1916. Serial No. 82,004. Term of patent 14 years.

To all whom it may concern:

Be it known that I, WALTER M. UPCHURCH, a citizen of the United States, residing at Mogollon, in the county of Socorro and State of New Mexico, have invented a new, original, and ornamental Design for a Poison Bottle or Receptacle, of which the following is a specification, reference being had to the accompanying drawing, forming part thereof.

The figure is a perspective view of a poison bottle or receptacle, showing my new design.

I claim—

The ornamental design for poison bottle or receptacle shown.

WALTER M. UPCHURCH.
